CLAIM

The ornamental design for a squirting toy, as shown and described.

DESCRIPTION

FIG. 1 is an exploded perspective view of the squirting toy, showing my new design;

FIG. 2 is a front view thereof in an assembled state, the side views and rear view being the same;

FIG. 3 is a top view thereof;

FIG. 4 is a bottom view thereof;

FIG. 5 is an exploded front view thereof;

FIG. 6 is an exploded front view, the left side view being the same;

FIG. 7 is bottom view of the cap thereof; and,

FIG. 8 is a top view.

The broken line showing in the Figures shows portions of the squirting toy and forms no part of the claimed design.
